ELECTROMECHANICAL RECORD SENSING DEVICE

Walter G. Paige, Norwalk, Conn., assignor to Remington Rand Inc., New York, N. Y., a corporation of Delaware

Application February 16, 1952, Serial No. 271,909

10 Claims. (Cl. 235—61.11)

1

This invention relates to a contact device adapted for operation by sensing pins such as are used in connection with perforated records.

A feature of the invention is the provision of a simple detachable contact spring formed of a single complete turn of spring wire, the end portions thereof being crossed and then formed into symmetrical straight leg portions.

Another feature of the invention is the provision of a novel support for a series of springs which support is formed of molded insulating material and provided with recesses shaped to retain the springs.

Still another feature of the invention is the provision of a relatively thin molded insulating plate for receiving a series of contact springs, the plate being open on one side and arranged to be assembled in stacks of a desired number, the arrangement being such that the back of one plate serves to cover the open recesses supporting springs of the next adjacent plate. With this arrangement a set of contacts for a conventional 80 column card may be conveniently assembled, or a lesser number if desired.

The invention is particularly adapted for use in business machines, but it will be understood that it may be used with any device using punched holes for coding of information, including devices such as player pianos and control units for automatic machinery.

Other objects and structural details of the invention will be apparent from the following description when read in connection with the accompanying drawing, wherein

Fig. 1 shows in elevation a molded contact supporting plate with some contacts mounted in the recesses formed therein;

Fig. 2 is an end view, partly in section of an assembly of contact supporting plates;

Fig. 3 is an enlarged detail portion of the insulating plate showing a pair of spring contacts, one being operated and the other unoperated; and

Fig. 4 shows schematically a known Remington Rand sensing pin arrangement for operating the contacts according to a preferred embodiment of the invention.

Referring to Fig. 1, a dielectric plate 10 is shown with a plurality of recesses 11 formed therein according to the number of sensing pins to be used therewith. In this specific embodiment the recesses are staggered alternately, vertically, for closer spacing. Each recess has a centrally located raised portion 12 formed therein having a curved depression 13 at the top for supporting a hardened roller or saddle 14 below

which is a symmetrical stop section 15, Fig. 3, spaced from the sides of the recess against opposite sides of which the legs 16 of contact springs 17 press when the particular contact is unoperated. When in a condition of rest, the curved upper portion 18 of the contact spring rests against a suitable curved upper surface 19 of the recess.

The springs 17 are tensioned so that their legs 16 normally rest against the stop part 15 of the dielectric block 10 associated therewith.

A pair of stationary contact strips 25 cooperate with the respective legs of each contact spring 17. These strips extend below the dielectric block 10 and terminate in soldering lugs 26 while their upper end portions extend up beyond the ends of the legs 16 of spring 17.

The stationary contact strips 25 are retained in suitably shaped grooves formed between the side walls of the recess 11 and the lower part 29 of the raised portion 12 in the recesses. The grooves 21, as well as the contact strips held thereby, vary somewhat in shape depending upon whether the strips are mounted in an upper contact recess 11 or a lower one, in order to make it possible to space the lugs 26 uniformly.

The upper bent over portions of the spring legs 16 straddle the saddle 14 and when pressure is applied to the upper curved part of spring 17 the legs will spread and make wiping contact with the conducting strips 25 adjacent thereto and establish a circuit between the associated pair of contact strips. Likewise when pressure is removed from the top of spring 17, the spring is so tensioned that the legs snap back to their position of rest against block 15.

A conventional card controlled apparatus using the contact structure of the present invention will now be described to illustrate one use thereof.

Fig. 4 shows a conventional Powers or Remington Rand card sensing system including the usual card chamber 35 formed of perforated upper and lower plates 36 and 37. A pin unit 38 of conventional design carries a number of pins 39 corresponding to the number of index points or possible holes in card 40, Fig. 3.

Pins 39 are urged downward by individual springs 41. The pin unit 38 is raised and lowered by a cam 42 and pitman mechanism 43 in synchronism with the movement of the cards 40 which are fed to the card chamber 35 by the usual skid rollers 50. The pin unit is provided with a card stop 44 which is effective to arrest the movement of the card in the chamber 35 when the pin unit 38 approaches its lowermost position. When the pin unit is lowered, the pins

39 finding openings in the card will pass through while all others will be arrested.

Referring to Fig. 3, the left hand pin 39 is shown as having passed through an opening in the card 40 while the right hand pin under which there is no perforation is stopped by the card. The left hand pin has engaged an anvil portion 47 of a rod 48 having a lower portion 49 of insulating material suitably coupled thereto which, when the rod assembly 48 is depressed by a sensing pin 39, engages the top of contact spring 17 and depresses the same slightly. Since the two legs of the contact spring 17 straddle the saddle 14 only a slight pressure from the rod 48 is required to force the legs apart and bring them into contact with the adjacent contact strips 25 thereby establishing a circuit between the associated pair of contact strips which may be used to control external circuits. When the pin unit 39 rises and pressure is withdrawn from spring 17, the legs 16 snap back, due to their tension, to their normal position of rest against the respective sides of block 15 thereby breaking the circuit between the associated pair of contact strips 25.

It is obvious that the contacts 25 could well be located on portion 15 and the pins 39 omitted. In this case, the member 47 would act as the sensing pin and the card would be reciprocated with respect to the sensing mechanism.

The advantages of the structure just described are that it can be built for very narrow spacing in accordance with the conventional index points of a standard business machine card; the springs are easily replaceable and require very little pressure for actuation; after the spring engages the associated contact strips, a definite wiping action takes place and, furthermore, the mechanical stresses in the current carrying parts are low.

While there is above described but one embodiment of the invention, it is possible to produce still other embodiments without departure from the inventive concept above disclosed, and it is, therefore, desired that only such limitations shall be imposed on the appended claims as are stated therein, or required by the prior art.

What I claim as new, and desire to secure by Letters Patent, is:

1. In a contact device suitable for actuation by the sensing pins of punched record apparatus, a coil of spring wire with crossed symmetrical portions extending therefrom which terminate in generally straight leg portions, a saddle straddled by the crossed portions, an insulating actuating pin supported for endwise movement over the mid point of the coil portion of the spring effective to engage and press upon the spring and

thereby in cooperation with the saddle to cause the legs of the spring to spread and contact means disposed in the path of the legs so as to be engaged thereby when the legs are in one position.

- 5 2. A contact device according to claim 1, in which the contact spring is supported in a suitably shaped recess formed in molded dielectric material.
- 10 3. A contact device according to claim 2 in which the recess in the molded material is formed with a centrally located raised portion spaced from the sides of the recess formed to support the saddle.
- 15 4. A contact device according to claim 3 in which the spring legs extend respectively into the spaces between the raised portion and the walls of the recess.
- 20 5. A contact device according to claim 4 in which the contact spring is so tensioned that when the spring is in its normal unoperated condition the spring legs rest against the raised portion clear of the sides of the recess.
- 25 6. A contact device according to claim 5 in which a pair of stationary contact strips are supported respectively in the path of movement of the spring legs by narrow channels formed generally symmetrically between a lower part of the raised central portion of the recess and the opposite walls of the recess whereby the legs of the contact spring when spread engage the contact strip adjacent thereto.
- 30 7. A contact device according to claim 6 in which the contact strips extend below the dielectric material and terminate in lugs for connection with external circuits.
- 35 8. A contact device according to claim 7 in which the dielectric material is formed in relatively thin plates corresponding in thickness to the width of a conventional business machine card column.
- 40 9. A contact device according to claim 8 in which the recesses of the dielectric plates are open on one face to provide easy access to the parts of the recesses, the plates being of such dimensions that they may be assembled in stacks corresponding to the number of columns to be sensed, the back of one plate serving as a cover for the open recesses of the next adjacent plate.
- 45 10. A contact device according to claim 9 in which the recesses in a molded plate are staggered alternately in a vertical direction to permit closer spacing of the insulated operating rods.
